UNITED STATES PATENT OFFICE.

ARTHUR S. KNIGHT, OF NEWARK, NEW JERSEY, ASSIGNOR TO WESTINGHOUSE LAMP COMPANY, A CORPORATION OF PENNSYLVANIA.

INCANDESCENT LAMP.

1,204,456. Specification of Letters Patent. Patented Nov. 14, 1916.

Application filed May 13, 1909. Serial No. 495,789.

To all whom it may concern:

Be it known that I, ARTHUR S. KNIGHT, a subject of the King of Great Britain, and a resident of Newark, in the county of Essex 5 and State of New Jersey, have invented a new and useful Improvement in Incandescent Lamps, of which the following is a specification.

My invention relates to incandescent 10 lamps, and particularly to supporting means for the filaments thereof.

The object of the invention is to provide 15 simple and economical means for resiliently supporting lamp filaments in such manner that they may withstand severe shocks and vibrations without breakage, and which will permit of such expansion and contraction 20 of filaments as may result from heating and cooling thereof and such contraction as may result from aging, without subjecting them to undue strains.

By reason of the crystalline and brittle 25 character of certain forms of metallic tungsten and of the more ductile forms of tungsten after being repeatedly brought to incandescence, filaments that are manufactured from tungsten for use in incandescent lamps are, or may become, extremely fragile. It is accordingly necessary to very carefully 30 mount them in the lamps in order that they may withstand ordinary shocks and vibrations and change in length upon heating, cooling and aging without subjection to undue strains and breakage.

35 In order to limit the vibrations of filaments, they are usually supported at frequent intervals by resilient supports which are so constructed and disposed as to subject the filaments to slight degrees of tension in order to maintain them taut under 40 all conditions. To this end, it has heretofore been customary to attach arbors to the stems of the lamps, which carry one or more resilient supports for the filaments. The arbors, being composed of glass, are not only 45 fragile and expensive, but the mounting thereof involves a special manufacturing operation. In the present case, arbors are dispensed with, and the resilient supporting 50 means for the filament is carried directly by the stem and is mounted upon substantially the same portion thereof as the terminal wires that project into the lamp.

My invention is illustrated in the accom-

panying drawings, Figure 1 of which is a 55 side view of a lamp constructed in accordance therewith and Fig. 2 is a similar view of a modified form of the lamp.

Projecting in the usual manner into the bulb 1 of the lamp, is a stem 2 through 60 which extend terminal wires or leads 3 and 4 the inner ends of which are bent abruptly back upon themselves to form V-shaped hooks which are adapted to engage and clamp, by a wedging action, the hooked extremities of a U-shaped filament 5.

Secured in the flattened end portion of the stem 2, between the leads 3 and 4, is a resilient member 6, the main portion of which projects alongside the filament at a 70 small angle with the axis of the stem 2 and the outer end of which is bent transversely and is provided with a hooked extremity to permit of its attachment to the bight portion of the filament 5, it being preferable to 75 interpose a link 7 of the same material as the filament between the hook and the filament, substantially as illustrated.

By reason of the resiliency of the member 6, the filament is maintained taut under 80 all conditions, as well as in good electrical contact with the extremities of the leads 3 and 4. Also, by reason of the omission of the arbor that has usually been attached to the end of the stem and of the substitution 85 therefor of a substantial, though resilient, supporting member for the bight portion of the filament, the lamp is rendered more economical to manufacture and more durable, when completed, than others of a similar 90 character that have been heretofore constructed.

In the lamp of Fig. 2, a filament 9 is reversely bent at three points into substantially a W-shape, and its ends are secured to 95 leads 10 and 11 that project from the stem 12 into the lamp in the same manner as in the lamp of Fig. 1. Projecting from the stem 12, and at a slight angle to the plane of the flattened end portion thereof, are two 100 resilient supporting members 13 and 14, having their ends bent toward the filament and attached to the adjacent bights thereof, as in Fig. 1. The filament is supported at the remaining bight by means of a shorter member 105 that also projects from the stem 12, a link 15 being preferably interposed between the support and the filament. The construc-

tion of Fig. 2 permits of the use of a comparatively long filament and of the production of a lamp of high candle power.

While the invention has been described with special reference to filaments composed of, or containing, tungsten, it is not restricted in its application to use in connection therewith, but may be applied wherever found useful.

10 I claim as my invention:

1. An incandescent lamp comprising a stem, conducting leads extending therethrough into the lamp, a reversely bent filament having its ends secured to the conducting leads, and a resilient member projecting from substantially the same portion of the stem as the conducting leads, the said member supporting the filament at the bight thereof and subjecting its legs to tension.

2. An incandescent lamp comprising a stem, conducting leads extending therethrough into the lamp, a reversely bent filament having its ends secured to the conducting leads, and alternately long and short members mounted upon the stem between the conducting leads and supporting the filament at the bights thereof.

3. An incandescent lamp comprising a stem, conducting leads extending therethrough into the lamp, a reversely bent filament having its ends secured to the conducting leads, and alternately long and short members mounted upon the stem between the conducting leads and supporting the filament at the bights thereof, the long members being resilient.

4. An incandescent lamp comprising a stem, conducting leads extending therethrough into the lamp, a reversely bent filament having its ends secured to the conducting leads, and alternately long and short members projecting from the stem adjacent the conducting leads and supporting the filament at the bights thereof.

5. An incandescent lamp comprising a stem, conducting leads extending therethrough into the lamp, a reversely bent filament having its ends secured to the conducting leads, and alternately long and short members projecting from the stem adjacent to the conducting leads and supporting the filament at each of its bights.

6. An incandescent lamp comprising a stem having a flattened portion, leading-in wires projecting therethrough into the lamp, a reversely bent filament extending between, and having its ends secured to, the leading-in wires, and a resilient member mounted at one end in the flattened portion of the stem and supporting the bight of the filament

at its other end, thereby subjecting the legs of the filament to tension.

7. An incandescent lamp comprising a stem having a flattened portion, leading-in wires projecting therethrough into the lamp, a reversely bent filament extending between, and having its ends secured to, the leading-in wires, and alternately long and short members projecting from the flattened portion of the stem and supporting the filament at its bights.

8. The combination with a filament in the form of an elongated loop, of a filament carrier comprising a stem, conductive supports secured to said stem and attached to the terminals of said filament, and a bent resilient filament holder having a length equal to or greater than the longitudinal axis of the loop and anchored at one end to said carrier adjacent to said supports and engaging at its other end the bight of the filament, said holder being resilient throughout its length.

9. A filament mount comprising a carrier, a filament comprising an elongated loop, means for supporting the legs of said filament farthest from its bend, and a bent resilient filament holder of a length approximately the length of a leg of said loop and in engagement at one end with the bight of said loop and anchored at the other end to said carrier near said supporting means to extend longitudinally of said loop.

10. In an incandescent lamp, a filament loop, a stem, a bent resilient filament holder for said loop of approximately the same length as said loop and anchored near one end to said stem with the other end in engagement with the bight of the filament loop, said holder being resilient throughout its length and yieldable transversely in all directions under stresses exerted by the filament.

11. A filament mount comprising a carrier, a filament comprising an elongated loop, means for supporting the legs of said filament farthest from its bend, and a filament holder having a substantially straight portion mounted on said carrier, and a curved portion projecting beyond the bend of said filament and engaging therewith, said holder being resilient throughout its length and being yieldable in all directions under stresses exerted by the filament.

In testimony whereof, I have hereunto subscribed my name this 30th day of April, 1909.

ARTHUR S. KNIGHT.
